(57) **CLAIM**

The ornamental design for an electric suspension mountain skateboard as shown and described.

DESCRIPTION

FIG. 1 is a perspective view of an electric suspension mountain skateboard showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear side perspective view thereof;

FIG. 9 is an enlarged detail view of area 9 shown in FIG. 1;

FIG. 10 is an enlarged detail view of area 10 shown in FIG. 2;

FIG. 11 is an enlarged detail view of area 11 shown in FIG. 3;

FIG. 12 is an enlarged detail view of area 12 shown in FIG. 3;

FIG. 13 is an enlarged detail view of area 13 shown in FIG. 4;

FIG. 14 is an enlarged detail view of area 14 shown in FIG. 5;

FIG. 15 is an enlarged detail view of area 15 shown in FIG. 6;

FIG. 16 is an enlarged detail view of area 16 shown in FIG. 7; and,

FIG. 17 is an enlarged detail view of area 17 shown in FIG. 8.

The broken lines in the drawings depict portions of the electric suspension mountain skateboard that form no part of the claimed design.
